UNITED STATES PATENT OFFICE

2,563,956

PROTECTIVE APRON

Ambrose L. Pietrowicz, Evanston, Ill., assignor to
 Poor & Company, Chicago, Ill., a corporation of
 Delaware

Application November 5, 1949, Serial No. 125,689

1 Claim. (Cl. 2—51)

1

This invention relates to a protective apron and more particularly to an apron adapted to be used by a workman employed in polishing metal articles with the aid of a buffer or polishing wheel.

In the manufacture of polished metal articles one process requires that a workman hold a workpiece to be polished against a buffer wheel which is rotating at a high rate of speed and to which various polishing compositions containing abrasives and other materials are applied. It is sometimes desirable that considerable force be exerted by the workman against the article to be polished in pressing the same against the polishing buffer. The wear on the clothing of the workman is substantial. A substantial amount of heat is also created in the workpiece and transmitted to the hands or body of the workman.

It is an object of the present invention to provide an apron which will protect the clothing of the wearer in an efficient manner and will also make it possible for a workman to hold a workpiece against a polishing buffer with a minimum of discomfort.

Other objects and advantages of the invention will be apparent by reference to the following description in conjunction with the accompanying drawings in which:

Figure 1 is an elevational view of an apron constructed in accordance with this invention;

Figure 2 is a plan view of the apron shown in Figure 1; and

Figure 3 is a partial sectional view taken along the line 3—3 of Figure 1.

The objects of the invention are accomplished by providing an apron with a reinforced section having a plurality of ridged portions surrounding one another. The ridges of material are preferably formed as a spiral but may be concentric or have another configuration such that each ridge substantially surrounds an adjacent ridge, being separated therefrom by an intervening recess or valley. The ridges are preferably formed by sewing together a plurality of layers of cloth or other sheet material. Where the seams are formed the layers are compressed so as to produce alternating recesses and ridges.

The preferred apron is of generally elliptical shape having a relatively heavy reinforced central substantially circular area, the largest dimension of which substantially corresponds or coincides with the shortest diameter of the elliptical area. The remainder of the elliptical area on the opposite sides of the reinforced substantially circular central portion of the apron

2

is preferably more flexible than the central portion so as to be capable of partially encircling the body of the wearer. In order to fasten the apron to the body of the wearer means are provided, such as a tape or other fastening means, tied or otherwise affixed to opposite edges of the apron, preferably at points at opposite ends of the longer axis of the elliptical area.

The preferred structure as illustrated in the drawings consists of an elliptically shaped body portion having a reinforced central portion 1 and composed of a plurality of sheets or plies of cotton duck or other sheet material in superposed layers 2, 3, 4, 5, and 6 (see Figure 3), which layers are enclosed by opposed covering sheets 7 and 8. The edge of the apron is bound by a tape 9 or other suitable binding material which is sewed and held in place by the thread 10.

The central portion of the apron which contains the additional layers of material 5 and 6 is also reinforced by sewing it with thread 11, preferably spirally in the form of a spiral of Archimedes, as illustrated in Figure 1. The outermost spiral of the reinforced central area 12 has a diameter substantially corresponding to the distance between the ends 12 and 13 of the shorter axis of the elliptical body portion. The side portions 14 and 15 are more flexible than the reinforced central portion of the apron and are provided with metal eyelets 16 and 17 to which tapes or strings 18 and 19 may be fastened by means of a knot or in any other suitable manner.

The more flexible areas 14 and 15 are adapted to partially encircle the body of the wearer. The reinforced central portion 1 of the apron is stiff enough to protect the body of the wearer and provides a support for holding workpieces against a polishing or buffer wheel. The spiral seam 11 and the raised portions or ridges 20 and 21 produced thereby provide a surface which is sufficiently rough to prevent slipping of the workpiece when it is held against the apron. The substantial thickness of the material in the central portion of the apron also assists in insulating the body of the wearer against any heat that may be generated due to the friction of a rapidly rotating polishing wheel in contact with the article being polished.

It will be apparent that the apron may be constructed of many different types of materials including cotton, wool, rayon, nylon, asbestos, glass fibers, plastic sheets (Koroseal, Saran) and the like. The employment of a fire-resistant and a heat-insulating material such as asbestos in the

central portion of the apron, or as at least one of the layers or plies comprising the central portion of the apron, is especially desirable. It will also be recognized that where a material, such as cotton duck or other non-fire-resistant material is employed, such material may be treated with various types of chemicals to make it fire-resistant.

The spiral configuration of the ridges in the central portion as compared to straight line ridges has the advantage of substantially preventing slippage in any direction due to the fact that the ridges are generally circular. The expression "generally circular" as employed herein is also intended to include and cover concentrically formed ridges such as would be produced by a plurality of concentric seams.

The invention is hereby claimed as follows:

An apron comprising essentially a generally elliptically shaped body portion composed of a

10

15

plurality of layers of cloth and having a central section extending between the ends of the shorter axis of the elliptical body portion, said central section having a plurality of ridges formed therein by a seam sewed spirally and said central section being composed of a greater number of layers of cloth than the portions of said elliptical body adjacent the ends of the longer axis.

AMBROSE L. PIETROWICZ.
